ROCK DRILL

Charles F. Osgood, Claremont, N. H., assignor to
 Sullivan Machinery Company, a corporation of
 Massachusetts

Application November 16, 1939, Serial No. 304,794

8 Claims. (Cl. 255—52)

This invention relates to rock drills, and more particularly to improvements in a hammer rock drill of the self-supporting stoper type.

An object of this invention is to provide an improved hammer rock drill having improved means for supporting the drill with respect to the work. Another object is to provide improved means for supporting and guiding the drill hammer motor of a stoper rock drill. A further object is to provide an improved stoper rock drill of the self-supporting type having improved means for supporting the drill at the working face as well as at its rear end abutment, whereby the drill may be supported with respect to the work wholly without manual aid. Yet another object is to provide an improved fluid actuated, extensible supporting means for supporting a stoper rock drill at its remote extremities with respect to the working face. A still further object is to provide an improved reversible feeding means for a stoper rock drill of the self-supporting type whereby the drill hammer motor may be fed rearwardly as well as forwardly with respect to the work while the drill is at all times maintained supported at its remote extremities. Another object is to provide an improved feeding and supporting mechanism for a hammer drill. Other objects and advantages of the invention will, however, hereinafter more fully appear.

In the accompanying drawings there are shown for purposes of illustration several forms and modifications which the invention may assume in practice.

In these drawings:

Fig. 1 is a side elevational view of an illustrative embodiment of the improved stoper rock drill.

Fig. 2 is a view in longitudinal vertical section taken through the rock drill shown in Fig. 1, the drill hammer motor being shown in side elevation.

Fig. 3 is a fragmentary sectional view taken in the plane of Fig. 2, showing a modified form of construction.

Fig. 4 is a view similar to Fig. 3, showing a further modified form of construction.

Fig. 4a is an enlarged, fragmentary, sectional view on the same plane as Fig. 4.

Fig. 5 is an enlarged cross sectional view taken substantially on line 5—5 of Fig. 1.

Fig. 6 is a vertical sectional view taken substantially on line 6—6 of Fig. 5.

Fig. 7 is a fragmentary view taken in the 55

plane of Fig. 6, showing the support control valve in a different position.

Fig. 8 is an enlarged detail sectional view taken substantially on line 8—8 of Fig. 6.

5 Fig. 9 is a side elevational view showing the improved rock drill mounted in horizontal drilling position on a mine column.

Fig. 10 is a view in longitudinal vertical section taken in the plane of Fig. 2, showing another illustrative embodiment of the invention.

10 Fig. 11 is a view similar to Fig. 10, showing a further embodiment of the invention.

Fig. 12 is a view similar to Fig. 2, on a somewhat reduced scale, showing still another illustrative embodiment of the invention.

15 In the illustrative embodiments of the invention shown in Figs. 1 to 8, inclusive, which include one form and two modifications of structural details, the drill hammer motor is generally designated 1 and the improved supporting, guiding and feeding structure is generally designated 2. The rock drill disclosed is of the stoper type, although it will be evident that various features of the invention may be embodied in rock drills of various other types.

20 The drill hammer motor 1 is of a conventional design and comprises a cylinder 3 containing a reciprocating hammer piston (not shown) for delivering impact blows to the shank of a drill 30 steel 4, the latter suitably supported within the front chuck housing 5 of the hammer motor. The motor cylinder has a rear head block 6 containing a throttle valve mechanism generally designated 7 for controlling the supply of pressure fluid to the motor cylinder. The rear head block and front chuck housing are secured to the motor cylinder in any conventional manner, as by side rods 8. As the internal structure of the drill hammer motors and the mode of operation 35 thereof are well known to those skilled in the art, and as the present invention is not dependent upon the use of any particular motor, further detailed description and illustration of the hammer motor are unnecessary.

40 45 Now referring to the supporting, guiding and feeding structure 2, it will be noted that a stationary feed cylinder 10 has its rear head 11 provided with an abutment-engaging point 12. Contained in the feed cylinder 10 is a reciprocable feed piston 13 having its piston rod 14 extending forwardly through the front head 15 of the feed cylinder 10. The forward end of the feed cylinder bore at the forward side of the feed piston is vented to atmosphere through a vent port 16. The feed piston rod 14 is of tu-

tular form and has a bore 17, and the feed piston 13 constitutes the rear head for the cylinder bore 17. Contained in the bore 17 is a reciprocable piston 18 carrying a cup leather 19 sealingly engaging the walls of the bore 17 for precluding leakage of fluid from the bore at the lower side of the piston past the piston. The piston 18 has a tubular piston rod 20 extending forwardly through a front head 21 integral with the feed piston rod 14, and secured to the outer end of the piston rod 20 is an abutment-engaging point 22. The forward end of the cylinder bore 17 at the forward side of the piston 18 is vented to atmosphere through a vent port 23. Fixed at 24 to the rear head 11 of the feed cylinder is a reaction rod 25, the latter arranged centrally within the feed cylinder and extending forwardly axially through a central opening 26 in the feed piston 13 and telescopically arranged within the piston rod 20. The feed piston 13 contains cup leathers 27 sealingly engaging the reaction rod 25 for preventing leakage of fluid along the rod through the opening 26 in the feed piston. The forward end of the reaction rod has an enlargement in the form of a piston head 28 substantially fitting the bore of the tubular piston rod 20, and this head has external grooves 29 for conducting pressure fluid from the bore 17 at the lower side of the piston 18 and through the tubular piston rod 20, along the rod 25 past the piston head 28, to the bore in the piston rod 20 in advance of the piston head. The abutment-engaging points 12 and 22 are in alignment and constitute the sole supporting means for the drill, the point 22 being engageable with the working face while the point 12 is engageable with a rearwardly located extraneous abutment. It will thus be seen that when pressure fluid is supplied to the bore 17 of the feed piston rod 14, the pressure fluid flows along the rod through the bore of the piston rod 20 and through the grooves 29, past the piston head 28, to the piston rod bore in advance of the piston head 28, and as a result the pressure fluid acts on the lower surface of the piston 18 and the surface 30 at the forward end of the bore of the piston rod 20, thereby moving the front point 22 into firm engagement with the working face, while at the same time the pressure fluid in the bore of the piston rod 20 acts on the upper surface of the piston head 28 of the reaction rod to hold the rear point 12 firmly against its abutment.

The drill hammer motor 1 is mounted on the feed piston rod 14, with its longitudinal axis in parallelism with the longitudinal axis of the supporting and guiding means 2, and in this instance the front chuck housing 5 has a laterally located integral boss-like projection 31 having a bore 32 receiving the forward portion of the feed piston rod 14. The projection 31 is held in position on the feed piston rod against a shoulder 33 by a retaining nut 34 threaded on the rod. Suitable means, such as a dowel, may be provided for preventing relative rotation between the projection 31 and the feed piston rod 14. It will thus be seen that the drill hammer motor 1 is entirely supported by the feed piston rod 14 of the feeding means and is guided during its feeding movement by the feed cylinder and the rods 14, 20 and 25.

The throttle valve mechanism 7 comprises a throttle valve 35 (Fig. 5) rotatably mounted in a bore 36 in the rear head block 6. The valve has a stem 37 to which is secured an operating

handle 38. The throttle valve has a hollow interior at 39, and pressure fluid may be supplied to the throttle valve interior through a supply connection 40 leading to any suitable source of pressure fluid supply. Pressure fluid may be supplied to the rear end of the feed cylinder at the lower side of the feed piston under the control of the throttle valve 35 through a port 41 in the valve communicable with a passage 42 connected through a flexible conduit 43 to a passage 44 (Fig. 2) in the rear head 11 of the feed cylinder. The throttle valve has ports 45 for supplying pressure fluid to the supply passages of the drill hammer motor in a well known manner. Pressure fluid may flow to the rear end of the bore 17 of the feed piston rod 14 below the piston 18 through a passage 46 (indicated in dotted lines in Fig. 5) communicating with the supply connection 40. Arranged in a bore 47 in the head block 6 is a separate, rotary, support control valve 48 provided with a valve stem to which is secured a manual control handle 49. The support control valve 48 has a bore 50 communicable through a port 51 with the passage 46. Seating against a seat surrounding the bore 50 is a spring-pressed check valve 52 for controlling the flow of fluid from the bore 50 to a groove 53 in the control valve. Passages 54 and 55 in the check valve 52 conduct pressure fluid, when the check valve is unseated, from the bore 50 past the valve seat and through the groove 53 to a chamber 56 at one end of the valve bore 47. A groove 57 in the control valve connects the chamber 56 with a passage 58 in the head block (see also Fig. 6) in one position of the valve 48. A circumferentially extending groove 59 on the throttle valve 35 connects the passage 58 with a passage 60, the latter extending longitudinally through the motor cylinder 3 and front chuck housing and communicating with a passage 61. As shown in Fig. 2, the passage 61 is connected by a longitudinal passage 62 in the feed piston rod 14 to a lateral port 63, the latter communicating with the rear end of the piston rod bore 17 at the lower side of the piston 18 in the manner shown. When the throttle valve 35 and the support control valve 48 are in the position shown in Fig. 6 pressure fluid may flow from the supply connection 40 through the passage 46, port 51, past the check valve 52, through passages 54, 55, chamber 56, groove 57, passage 58, groove 59 on the throttle valve, passage 60, port 61, passage 62 and port 63, to the piston rod bore 17 at the lower side of the piston 18 to move the latter upwardly and forwardly within its bore in the feed piston rod. Concurrently, pressure fluid flows from the bore 17 through the bore of the piston rod 20, through the grooves 29 in the piston head 28 of the reaction rod 25, to the upper end of the piston rod bore, to move the reaction rod in a rearward direction. When the valve 48 is turned in the position shown in Fig. 7, the bore 17 at the lower side of the piston 18 is vented to atmosphere through port 63, passage 62, port 61, passage 60, groove 59 on the throttle valve, passage 58, a groove 64 on the valve 48, and an exhaust passage 65 in the valve. The throttle valve 35 is provided with an exhaust groove 66, and when the throttle valve is rotated to bring the groove 66 into communication with the passage 42, the rear end of the feed cylinder at the lower side of the feed piston is vented to atmosphere. Pressure fluid may also flow from the interior of the throttle valve 35 through the port 41, passage 42, conduit 43, and passage 44, to the lower end

of the feed cylinder at the lower side of the feed piston 18. Pressure fluid flowing through the passage 62 and port 63 to the bore 17 acts on the lower side of the piston 18 to move the front point 22 firmly against the working face and, concurrently, the pressure fluid flowing through the piston rod bore past the reaction rod 25 and through the grooves 29 in the piston head 28 to the bore of the piston rod 20 at the upper side of the piston head, acts on the upper surface of the piston head to hold the rear point 12 at the rear end of the drill firmly against its extraneous abutment. When the abutment-engaging points 12 and 22 are in extended position against their extraneous abutments, the supporting and guiding structure 2 is firmly held in place with respect to the work, and the pressure fluid flowing to the feed cylinder bore at the lower side of the feed piston acts on the feed piston to feed the drill hammer motor forwardly along the supporting and guiding structure toward the work. When the feed cylinder bore at the lower side of the feed piston 18 is vented to atmosphere, the pressure fluid in the piston rod bore 17 acts on the upper surface of the piston to effect rearward movement of the latter with respect to the piston 18, and as a result the drill hammer motor is moved along the supporting and guiding structure in a rearward direction. In the event that the fluid supply should fail for any reason, the check valve 52 automatically closes to trap the fluid in the piston rod bore 17 at the lower side of the piston 18 and at the upper side of the piston head 28, so that the abutment-engaging points are held firmly in place, thereby to prevent inadvertent falling of the drill away from the work. It should be noted that the valve 35 can be manipulated to supply pressure to or to vent the port 42 without interrupting communication of groove 59 with passages 58 and 60.

The provision of the reverse feed for the drill hammer motor is of particular importance when the drill is in horizontal drilling position, as shown in Fig. 9, so that the hammer motor can be readily retracted from the work. In this instance the rear abutment-engaging point 12 of the drill is seated within a socket member 70, in turn pivotally mounted at 71 on a clamp 72, the latter being secured to an upright mine column 73. This mine column has a bottom abutment-engaging point 74 and a top abutment-engaging point 75, the latter being secured to an extensible member 76. The mine column is preferably of the fluid-actuated type, and the extensible member 76 is extended under the action of pressure fluid so that the abutment-engaging points at the opposite extremities of the column are held firmly in position. The supply connection 40 of the drill hammer motor is connected through a hose 77 to a main supply line 78, and also connected to this supply line through a hose 79 under the control of a valve 80 is the fluid supply for the mine column. When the parts are in the position shown in Fig. 9, the drill is supported at the working face by the abutment-engaging point 22, and at its rear end by the mine column. When pressure fluid is supplied to the rear end of the feed cylinder 10 at the rear side of the feed piston 18, the drill hammer motor may be fed forwardly along the supporting and guiding structure 2, and when the rear end of the feed cylinder 10 is vented to atmosphere in the manner above described, the pressure in the piston rod bore 17, due to the differential pressure areas on the feed piston acts on the feed piston head to feed the

drill hammer motor rearwardly along the supporting and guiding structure. This reverse feed feature eliminates, during horizontal drilling, the necessity of manually moving the drill hammer motor in a rearward direction, as would be necessary if the reverse feed feature were omitted. In a drill of the stoper type, as shown in Fig. 1, the reverse feed feature is not so essential since the weight of the drill hammer motor, when the rear end of the feed cylinder is vented to atmosphere, causes the hammer motor to move rearwardly by gravity.

In Fig. 3 a modified form of construction is disclosed. In this instance the piston 18 assumes the form of a piston head 81 fitting the bore 17 of the feed piston rod 14, and this piston head has a series of longitudinal external grooves 82 to permit the pressure fluid to flow from the piston rod bore 17 at the upper side of the piston, past the piston to the piston rod bore at the lower side of the piston, thereby eliminating piston packings and the fluid supply passage in the walls of the piston rod 14, as in the construction disclosed in Fig. 2. As illustrated, the fluid supply passage 61 is connected by a passage 83 in the front head 21 of the piston rod with a passage 84 communicating with the upper end of the piston rod bore 17. When pressure fluid is supplied to the passage 61, it flows through passages 83 and 84 to the upper end of the piston rod bore 17, past the piston head 81, through the grooves 82, to the piston rod bore at the lower side of the piston, the pressure fluid acting on the lower pressure area of the piston head 81 to move the latter upwardly within its bore to effect engagement of the abutment-engaging point 22 with the working face. Concurrently, pressure fluid flows through the bore of the piston rod 20, past the grooved head 28 on the reaction rod 25, to the bore of the piston rod 20 above the piston head 28, the pressure fluid acting on the upper pressure area of the reaction rod head to hold the rear abutment-engaging point 12 firmly against its extraneous abutment. The retaining nut 34 is provided with a forward enlargement 85 carrying a packing 86 sealingly engaging the exterior surface of the piston rod 20 to prevent leakage of pressure fluid from the upper end of the piston rod bore 17 past this piston rod. Otherwise this modified structure is the same as that disclosed in Fig. 2.

In the modified construction shown in Fig. 4, the piston rod 20 supporting the abutment-engaging point 22 is actuated by pressure fluid in a reverse direction, as well as in a forward direction, so that the abutment-engaging point 22 may be retracted by power. In this construction, the piston 18 carries packings 87 for preventing leakage of pressure fluid from the opposite ends of the piston rod bore 17 past the piston 18. Arranged in a bore 88 in the boss-like projection 31 on the chuck housing of the drill hammer motor, is a rotary reverse valve 89. Communicating with the valve bore is a passage 90 connected to a passage 91 communicating with the upper end of the piston rod bore 17 at the upper side of the piston 18. Also communicating with the valve bore is a passage 92 connected to a passage 93 extending longitudinally through the side wall of the feed piston rod 14, the passage 93 being connected through a lateral port 94 with the piston rod bore 17 at the lower side of the piston 18. Also communicating with the valve bore is a vent passage 95. The valve 89 has a central supply chamber

96 connected by a port 97 to a peripheral groove 98. Formed also in the valve is an exhaust groove 99 communicable alternatively with the passages 90, 92 and continuously with the exhaust passage 95. When the valve 89 is rotated to bring the supply groove 98 into communication with the passage 92, pressure fluid may flow through the passage 93 and port 94 to the piston rod bore 17 at the lower side of the piston 18, the pressure fluid acting on the lower pressure area of the piston 18 to move the latter forwardly within the piston rod bore, thereby moving the abutment-engaging point 22 forwardly against the working face. When pressure fluid is supplied to the lower end of the piston rod bore at the lower side of the piston 18, the upper end of the piston rod bore is concurrently vented to atmosphere through passages 91, 99 and exhaust groove 99 communicating with the exhaust passage 95. When the valve 89 is rotated to bring the supply groove 98 into communication with the passage 90, pressure fluid may flow through the passage 91 to the upper end of the piston rod bore 17 at the upper side of the piston 18, the pressure fluid acting on the upper pressure area of the piston to effect rearward movement of the latter in the piston rod bore, and as a result the abutment-engaging point 22 is retracted from the working face. As pressure fluid flows to the upper end of the piston rod bore, the piston rod bore at the lower side of the piston is concurrently vented to atmosphere through port 84, passage 93, passage 92 and exhaust groove 99 communicating with the exhaust passage 95. Otherwise this modified form of construction is the same as that disclosed in Fig. 2.

In the illustrative embodiment of the invention disclosed in Fig. 10, the drill hammer motor 1 is supported by a reciprocable feed cylinder 105, the boss-like projection 31 on the chuck housing 5 of the drill hammer motor being secured at 106 to the forward end of the reciprocable feed cylinder. Contained in the feed cylinder is a stationary feed piston 107 having a tubular piston rod 108 extending rearwardly through the packed rear head 109 of the feed cylinder. Secured to the rear end of the feed piston rod 108 is a head member 110 carrying an abutment-engaging point 111. The rear feed cylinder head carries a packing 112 sealingly engaging the exterior periphery of the piston rod 108 to prevent leakage of pressure fluid from the feed cylinder. Secured at 113 to the upper head 114 of the feed cylinder is a tubular member 115 extending centrally through the feed cylinder bore and telescopically arranged with the tubular piston rod 108. The feed piston 107 carries packings 116 sealingly engaging the exterior periphery of the tubular member 115 to prevent leakage of pressure fluid in opposite directions past the piston. The rear end of the tubular member 115 has an integral piston head 117 guided within the bore of the piston rod 108 and having longitudinal external grooves 118 to permit the flow of pressure fluid past the same. The bore of the feed piston rod 108 is connected, through ports 119 in the tubular member 115, with the lower end of the bore 120 of this tubular member. The bore of the feed piston rod 108 is connected through ports 121 with the feed cylinder bore at the lower side of the feed piston. Reciprocably mounted in the bore 120 of the tubular member 115 is a packed piston 122 having its piston rod 123 extending forwardly through the upper head of the feed

cylinder and carrying at its upper end an abutment-engaging point 124. Connected to the head member 110 is a fluid supply connection 125 communicating through a passage 126 with the lower end of the bore of the feed piston rod 108. When pressure fluid is supplied through the connection 125 and passage 126 to the bore of the feed piston rod 108, it flows through the grooves 118 past the piston head 117 and through ports 119 to the bore 120 of the tubular member 115, the pressure fluid acting on the lower pressure area of the piston 122 to move the latter upwardly within its bore; and as a result the abutment-engaging point 124 is moved against the working face. When it is desired to effect forward feed of the drill hammer motor, pressure fluid may be supplied through a supply passage 127 in the boss-like projection 31 and through port 128 to the feed cylinder bore at the upper side of the feed piston, the pressure fluid acting on the forwardly acting pressure area 129 of the front cylinder head 114 to effect forward feeding movement of the feed cylinder relative to the feed piston; and as a result the drill hammer motor is moved forwardly toward the work. During the forward feeding operation the pressure fluid acting on the front cylinder head 114 is supplemented by the pressure fluid acting on the effective rear pressure area 130 of the piston head 117 of the tubular member 115. Concurrently, pressure fluid flows from the bore of the feed piston rod 108 through ports 121 to the feed cylinder bore at the rear side of the feed piston 107. When the forward end of the feed cylinder bore at the upper side of the feed piston is vented to atmosphere, the pressure fluid flowing to the rear end of the feed cylinder bore acts on the rearwardly acting pressure area 131 of the rear cylinder head 109 to effect rearward movement of the feed cylinder relative to the stationary feed piston; and as a result the drill hammer motor is fed rearwardly with respect to the work. It is evident that the combined effective pressure areas 130, 129 on the head 117 and the front cylinder head are substantially greater than the rearwardly acting pressure area 131 on the rear cylinder head 109, so that when pressure fluid is supplied to the forward end of the feed cylinder bore forward feed is effected. Also, the rearwardly acting pressure area 131 on the rear feed cylinder head 109 is somewhat larger than the effective rear pressure area 130 on the piston head 117, so that when the upper end of the feed cylinder bore is vented to atmosphere, reverse feed is effected. Obviously any suitable control means for the selective supply and venting of fluid relative to the passages 127 and 125 may be used. For example the control means for port 42 can be utilized through a suitable conduit to govern the connection 127, and the control for passage 60 can be utilized through suitable conduits to control passage 125.

In the illustrative embodiment of the invention shown in Fig. 11, the feed cylinder structure is essentially the same as that disclosed in Fig. 10, in that the feed cylinder is reciprocable and the drill hammer motor 1 is supported by the feed cylinder. In this construction, the reciprocable feed cylinder 132 contains a feed piston 133 stationary in normal use and having a tubular piston rod 134 extending rearwardly through the packed rear head 135 of the feed cylinder. Secured to the rear end of the feed piston rod is a head member 136 carrying an abutment-engaging point 137. Reciprocable in

the bore 138 of the feed piston rod 134 is a piston head 139 having its piston rod 140 telescopically arranged within the feed piston rod and extending forwardly through the packed bore 141 of the feed piston and upwardly through the packed upper head 142 of the feed cylinder. Carried at the upper end of the piston rod 140 is an abutment-engaging point 143. The feed piston carries packings 144 sealingly engaging the piston rod 140 for preventing leakage of pressure fluid through the bore 141 past the feed piston in opposite directions. Connected to the head member 136 is a supply connection 145 communicating through a passage 146 with the bore 138 of the feed piston rod. A fluid supply passage 147 communicates through a port 148 with the feed cylinder bore at the upper side of the feed piston. Any suitable supply and exhaust controls for connections 145 and 147 may, as noted with connections 125 and 127, be used. The bore 138 in the feed piston rod is connected through ports 149 with the feed cylinder bore at the lower side of the feed piston. The piston head 139 is provided with longitudinal external grooves 150 to permit flow of pressure fluid through the piston rod bore past the piston head. When pressure fluid is supplied through the supply connection 145 and passage 146 to the bore 138 of the feed piston rod, the pressure fluid acts on the effective rear pressure area 151 of the piston head 139 to move the latter forwardly within the piston rod bore; and as a result the abutment-engaging point 143 is moved into engagement with the working face. At the same time pressure fluid flows through the grooves 150, through the piston rod bore, along the piston rod 140, and through ports 149, to the feed cylinder bore at the rear side of the feed piston. When pressure fluid is supplied through the passage 147 and port 148 to the feed cylinder bore at the upper side of the feed piston, the pressure fluid acts on the forwardly acting pressure area 152 of the front cylinder head to move the feed cylinder forwardly; and as a result the drill hammer motor is fed toward the work. When the passage 147 is vented to atmosphere, pressure in the upper end of the feed cylinder bore is exhausted, and as a result the pressure fluid flowing through the ports 149 to the rear end of the feed cylinder bore acts on the rearwardly acting pressure area 153 of the rear feed cylinder head to move the feed cylinder rearwardly, thereby retracting the drill hammer motor from the work.

In the illustrative embodiment of the invention disclosed in Fig. 12, the supporting, guiding and feeding structure 2 is, except as will be noted, the same as that disclosed in Fig. 2 and the drill hammer motor 1 is carried by the piston rod 14 of the feed piston 13. The feed piston is reciprocable in the stationary feed cylinder 10, the latter having a rear abutment-engaging point 12. In this construction, the feed piston rod 14 has a bore 154, and reciprocable in the piston rod bore is a piston head 155 having its piston rod 156 extending forwardly through a packing 157 carried at the forward end of the feed piston rod. Secured to the forward end of the piston rod 156 is the abutment-engaging point 22. The piston head 155 is provided with longitudinal external grooves 158 to permit flow of pressure fluid past the piston head. In this instance the reaction rod 25 is omitted and the rear end of the piston rod bore 154 is closed by a rear head member 159. Communi-

cating with the piston rod bore 154 at the upper side of the piston head 155 is a fluid supply passage 160. When pressure fluid is supplied through the passage 160 to the piston rod bore 154, pressure fluid flows rearwardly through the bore 154, along the piston rod 156, and through the grooves 158 on the piston head 155, to the piston rod bore 154 at the rear side of the piston head, the pressure fluid acting on the rear pressure area 161 of the piston head to move the latter forwardly within the piston rod bore 154; and as a result the abutment-engaging point 22 is moved forwardly against the working face. When pressure fluid is supplied to the rear end of the feed cylinder 14 at the rear side of the feed piston, the pressure fluid acts on the rear pressure area 162 of the feed piston to move the latter forwardly within the feed cylinder bore, and as a result the drill hammer motor is fed toward the work. When the rear end of the feed cylinder bore is vented to atmosphere, pressure fluid in the piston rod bore 154 acts on the forward pressure area 163 of the piston head 159 to effect rearward movement of the feed piston 13, and as a result the drill hammer motor is retracted from the work. Otherwise this embodiment of the invention is the same as that disclosed in Fig. 2.

As a result of this invention, it will be noted that an improved supporting structure is provided for a stoper rock drill whereby the rock drill may be supported with respect to the work wholly without manual aid. It will further be noted that by the provision of the front abutment-engaging point engageable with the working face and actuated by pressure fluid, the stoper rock drill is held firmly against the work. It will further be evident that by the provision of the reverse feeding means the drill hammer motor may not only be fed forwardly toward the work under the action of pressure fluid, but may be also retracted from the work under the action of pressure fluid, in a simplified manner, the drill hammer motor being supported and guided by the improved supporting and guiding means during both its forward and reverse feeding movements. Other uses and advantages of the improved rock drill will be clearly apparent to those skilled in the art.

While there are in this application specifically described several forms and modifications which the invention may assume in practice, it will be understood that these are shown for purposes of illustration and that the invention may be further modified and embodied in various other forms without departing from its spirit or the scope of the appended claims.

What I claim as new and desire to secure by Letters Patent is:

1. In a rock drill, relatively reciprocable feed cylinder and feed piston elements, fluid actuated means coaxial with said cylinder and piston elements for supporting the drill on the working face and including oppositely acting fluid actuated supporting elements, one of which is a stationary reaction element, a drill hammer motor operatively connected to the piston element for feeding thereby, said feed piston element having differential pressure areas, the larger one of said piston areas acting in the forward-feed-effecting direction and the smaller pressure area acting in the reverse-feed-effecting direction, means for supplying pressure fluid concurrently to said fluid actuated supporting means and said smaller piston area, and means for supplying pressure

fluid to and exhausting fluid from said larger piston area without interrupting the flow of pressure fluid to said smaller pressure area, the pressure fluid acting on said larger pressure area overcoming the pressure of the fluid acting on said smaller pressure area to effect forward feed of the drill hammer motor and the pressure fluid acting on said smaller piston area effecting reverse feed of the drill hammer motor when said larger piston area is connected to exhaust.

2. In a rock drill, relatively reciprocable feed cylinder and feed piston elements, said piston element having a piston rod provided with a bore, fluid actuated means coaxial with said cylinder and piston elements for supporting the drill on the working face and including a fluid actuated supporting piston reciprocably mounted in said piston rod bore and extending forwardly through the forward end of said feed piston rod, said piston rod of said supporting piston having a bore, a reaction rod secured to and extending centrally through said feed cylinder element and having a piston head received in said bore of said supporting piston rod, a drill hammer motor operatively connected to the piston element for feeding thereby, said feed piston element having differential pressure areas, the larger one of said piston areas acting in the forward-feed-effecting direction and the smaller pressure area acting in the reverse-feed-effecting direction, means for supplying pressure fluid concurrently to said fluid actuated supporting means and said smaller piston area without interrupting the flow of pressure fluid to said smaller pressure area, and means for supplying pressure fluid to and exhausting fluid from said larger piston area, the pressure fluid acting on said larger pressure area overcoming the pressure of the fluid acting on said smaller pressure area to effect forward feed of the drill hammer motor and the pressure fluid acting on said smaller piston area effecting reverse feed of the drill hammer motor when said larger piston area is connected to exhaust.

3. In a rock drill, a stationary feed cylinder having a rear abutment-engaging point, a feed piston reciprocable in said feed cylinder and having its piston rod extending forwardly through the front cylinder head, said feed piston rod having a bore, a drill hammer motor carried by said feed piston rod, a piston reciprocable in said piston rod bore and having its piston rod extending forwardly through the forward end of said feed piston rod, an abutment-engaging point carried at the forward end of said last-recited piston rod, and relatively stationary reaction means for said last mentioned piston.

4. In a rock drill, a stationary feed cylinder having a rear abutment-engaging point, a feed piston reciprocable in said feed cylinder and having its piston rod extending forwardly through the front cylinder head, said feed piston rod having a bore, a drill hammer motor carried by said feed piston rod, a piston reciprocable in said piston rod bore and having its piston rod extending forwardly through the forward end of said feed piston rod, an abutment-engaging point carried at the forward end of said last-recited piston rod, said last-recited piston rod having a bore, and a reaction rod secured to and extending centrally through said feed cylinder and having a piston head in the bore of said last-recited piston rod.

5. In a rock drill, an elongated extensible supporting structure comprising a pair of cooperat-

ing, oppositely extending, telescopically arranged piston rods, each having a piston head contained in a cylinder, said rods at their remote extremities adapted to react against extraneous abutments, the face of the work constituting the forward abutment, means for supplying pressure fluid to the cylinders to effect opposite relative movement of said rods to move the same into firm engagement with their extraneous abutments.

6. In a rock drill, an elongated extensible supporting structure comprising a pair of cooperating, oppositely extending, telescopically arranged piston rods each having a piston head contained in a cylinder, said rods at their remote extremities adapted to react against extraneous abutments, means for supplying pressure fluid to the cylinders to effect opposite relative movement of said rods to move the same into firm engagement with their extraneous abutments, a feed cylinder stationary with respect to one of said rods and containing a reciprocable feed piston, and a drill hammer motor operatively connected to said feed piston for feeding thereby.

7. In a rock drill, an elongated extensible supporting structure comprising a pair of cooperating, oppositely extending, telescopically arranged piston rods each having a piston head contained in a cylinder, said rods at their remote extremities adapted to react against extraneous abutments, means for supplying pressure fluid to the cylinders to effect opposite relative movement of said rods to move the same into firm engagement with their extraneous abutments, a feed cylinder stationary and coaxial with respect to one of said rods and containing a reciprocable feed piston, said feed piston having a tubular piston rod providing a cylinder in which one of said pistons of said telescopically arranged piston rods is contained, and a drill hammer motor operatively connected to said feed piston for feeding thereby.

8. In a rock drill, an elongated, extensible supporting structure comprising a pair of cooperating, oppositely extending, telescopically arranged piston rods each having a piston head contained in a cylinder, said rods at their remote extremities adapted to react against extraneous abutments at the opposite extremities of the drill, means for supplying pressure fluid to the cylinders to effect opposite relative movement of said rods to move the same into firm engagement with their extraneous abutments, relatively reciprocable feed cylinder and piston elements coaxial with said supporting structure, and a drill hammer motor operatively connected to said reciprocable feed piston element for feeding thereby.

9. In a rock drill, an elongated, extensible supporting structure actuated by pressure fluid and at its remote extremities adapted to react against extraneous abutments whereby the drill is supported solely at its remote extremities, a drill hammer motor, and fluid actuated feeding means for said hammer motor including relatively reciprocable feed cylinder and piston elements arranged coaxially with said supporting structure, said feed piston element having differential pressure areas, means for supplying pressure fluid concurrently to said supporting means and the smaller pressure area of said feed piston, and means for supplying pressure fluid to and exhausting fluid from the larger pressure area of said feed piston without interrupting the flow of pressure fluid to said smaller pressure area, the pressure fluid acting on said larger pressure area overcoming the pressure of the fluid acting on said smaller pressure area to cause said piston to effect forward feed of said drill hammer motor and the pressure fluid acting on the smaller pressure area of said feed piston effecting reverse feed of said drill hammer motor when said larger pressure area is vented to atmosphere.
